UNITED STATES PATENT OFFICE.

MAHALIA E. JOHNSON, OF RENO, NEVADA.

DESIGN FOR A CHAFING-DISH.

43,721.

Specification for Design.

Patented Mar. 18, 1913.

Application filed November 26, 1912. Serial No. 733,685. Term of patent 7 years.

To all whom it may concern:

Be it known that I, MAHALIA E. JOHNSON, a citizen of the United States, residing at Reno, in the county of Washoe and State of Nevada, have invented a new, original, and ornamental Design for Chafing-Dishes, of which the following is a specification, reference being had to the accompanying drawing, forming a part thereof.

Figure 1 is an end view of a chafing dish,

showing my new design. Fig. 2 is a side elevation.

I claim:

The ornamental design for a chafing dish, as shown.

MAHALIA E. JOHNSON. [L. S.]
